INVENTOR.
Daniel G. Saunders Jr.

UNITED STATES PATENT OFFICE.

DANIEL G. SAUNDERS, JR., OF KANSAS CITY, MISSOURI.

CONVERTIBLE BODY FOR MOTOR-DRIVEN VEHICLES.

1,285,411.

Specification of Letters Patent. Patented Nov. 19, 1918.

Application filed April 11, 1916. Serial No. 90,307.

To all whom it may concern:

Be it known that I, DANIEL G. SAUNDERS, Jr., a citizen of the United States, residing at Kansas City, in the county of Jackson and 5 State of Missouri, have invented certain new and useful Improvements in Convertible Bodies for Motor-Driven Vehicles; and I do declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

My invention relates to convertible bodies for motor driven vehicles, and has for its principal object to provide a body comprising posts or standards which form a permanent part of the body but which may be housed therein when not in use.

It is also an object of the invention to provide posts or standards of this character which may be easily and quickly moved to or 25 from the housing and which, when in functional position, not only form supports or guides for the windows or curtains, but also serve to close the vehicle between adjacent windows or curtains.

30 In accomplishing these and other objects of the invention, I have provided improved details of structure, the preferred forms of which are illustrated in the accompanying drawings, wherein:—

35 Figure I is a side elevation of a convertible body embodying my improvements, parts of the main body and supplemental closure members being broken away for better illustration.

40 Fig. II is a longitudinal section along the line II—II Fig. I, showing the fore and rear doors closed in full lines and open in dotted lines.

Fig. III is a side elevation of a part of the 45 body, portions of the fore and rear doors being broken away to illustrate the housing of the supplemental closure standards.

Fig. IV is a vertical section of part of the 50 doors on the line IV—IV, Fig. III, particularly illustrating the housing of the supporting standards and curtain, the housing cover being shown closed, and open in dotted lines.

Fig. V is a similar view showing the parts 55 in functional position.

Fig. VI is a detail perspective view of one of the doors, showing one of the supporting standards in functional position and the curtain partly raised.

Referring more in detail to the drawings: 60 1 designates the vehicle body, which may be of any ordinary type, but comprises the fore and rear doors 2—3, each of which doors comprises inner and outer facings 4—5, which are spaced by the end and bottom 65 frame members 6 to form an interior chamber 7. The end frame members 4 are cut away at their upper ends to provide the recesses 8, and pivotally mounted in said recesses are posts or standards 9, each of which 70 comprises a main body portion and a reduced shank 10, the end of the shank being located in the recess and pivoted to the frame member, and the reduction between the body portion and shank forming a downwardly 75 facing shoulder 11, which is adapted for abutment against and support by the body of the vehicle adjacent the door opening.

The standards 9 may be constructed of relatively thin material, and when housed within the chamber 7 may occupy the least possible space, so that the front and rear standards on each door lap each other within the door housing and leave room therein for an extension window or curtain 14, which is 85 also adapted for housing within the chamber.

By providing the standards with the offsets or shoulders 11, parts of the bodies of the standards on the rear end of the first door 2 and of the standard on the front end of the rear door 3 are extended over the post member 12 of the vehicle body that separates the door openings, so that said standards overlap each other and close the vehicle between the door curtains. In like manner 90 the offsets of the standards on the front end of the front door and on the rear end of the rear door project over the body at the front and rear of the respective door openings and form abutments for the wind shield in front 95 and for the windows or curtains at the rear when the latter are raised from their housings in the body or otherwise installed.

Each door curtain 14, in its preferred 100 form, comprises a frame 15, preferably composed of tough fabric or leather and containing a central panel 16 of transparent material, such as glass or mica, the frame 15 having pocket members 17 at its upper 105 and lower edges, through which rods 18—19 110

may be projected to stiffen the ends of the curtain at the top and bottom. The ends of the curtain frame 15 extend beyond the ends of the pockets 17 and are preferably 5 bifurcated to extend over opposite faces of standards 9 and form elongated guide pockets within which the standards are contained and form effective connection between the standards and curtain, that not only serves 10 to anchor the curtain but also effectually prevents the admission of snow or rain to the interior of the vehicle between the curtain and said standards. As there is room within the housing chamber 7 for containing 15 the curtains without folding or rolling I prefer to hang the curtains within the chambers, and thereby avoid creasing the curtains or marring the surface thereof, and in order to support the curtains so that they 20 may be readily accessible to a person wishing to extend the same, I provide the housing with hooks 22 (Fig. IV) which are adapted to take through eyelets 23 at the edges of the curtain frames so that the curtains 25 may be supported from the upper end of the housing and hang freely therein. In order to prevent the curtains from swinging freely within the housing and rattling against the sides thereof, I locate a 30 V-shaped trough 24 in the bottom of each of the housings into which the lower end of a curtain may seat when housed, the flaring mouth of the trough receiving the lower edge of the curtain and forming a tight seat 35 for the lower rod when the curtain is lowered.

I also provide for fastening the curtains in functional position by locating the eyelets 23 in the upper end of the inner bifurcated portions 26 so that they may take over buttons 26' on the upper, inner corners of the standards 9, and so that when the curtains are raised their upper corners may be 40 buttoned onto the upper portions of the standards and the curtains suspended from the buttons and securely attached to the standards.

When a curtain is housed within the 45 chamber in its door member, the upper end of the chamber may be closed by a lid or cover 27, which is preferably hinged to the inner edge of the housing, and may be closed against the curtain to bind the same tightly against the outer edge of the door in such 50 position that moisture will flow down the curtain and to the outside of the door.

I have not described the closure members or other parts of the vehicle as the present invention relates particularly to the supporting posts, which may be used with curtains of any suitable construction.

In order, however, to effectually close the vehicle at the edge of the top, the top may be provided with depending inner and outer 60 edge flaps forming an abutment for the

door curtains and a pocket for the body curtains, as described in my copending application, Serial No. 90308, filed April 11, 1916.

In order that the lids or covers may swing to and from normal position, I cut away the inner edges of the standards at their lower ends to form the recesses 28 through which the ends or covers may travel, and in order that the lower ends of the curtains may be extended outwardly to be bound by the lids or housing covers I cut away the lower ends of the inner bifurcated portions of the curtains. It is apparent that, when the parts are in functional position, the ends of the housing lids or covers will lie 70 against or close to the standards and thereby prevent accidental displacement of the standards.

Assuming that the parts are constructed 75 and assembled as described, it is apparent that the vehicle may be used with the body open at the sides and with the top down. When, however, it is desired to close the body to protect the occupants against cold 80 or inclement weather, the top is raised and the supplemental closure for the body of the car installed.

The lids or covers 27 on the doors 2-3 are 85 then swung back and the standards 9 swung up on their pivotal mountings until they stand perpendicularly, with the shoulders 11 seated on the permanent body parts at the edges of the door openings, the front standard on the fore door lying within a frame member on the front of the vehicle, the rear standard on the rear door overlapping the rear curtain and the rear wing of the standard on the fore door overlapping the front edge of the wing on the forward standard of the rear door, so that the standards 90 press against relatively stationary parts or against each other and effect tight joints, the openings of which are rearward so that 100 when the vehicle is in motion wind or rain may not enter through the joints.

When the standards have been placed as 105 described, the curtains are lifted from the housings with the bifurcated anchor members running along the side edges of the curtains fitting along the edges of the standards, until the curtains are in closed position, when they are buttoned to the standards and are held in place.

When the body is to be reconverted into 110 an open body, the extension curtains are unbuttoned from their supports or standards and let down into the housings where they are supported from the hooks 22, so that 115 they may hang without folding in the housings and in a position where they may be easily accessible when the body is to be converted into a closed structure.

After the curtains have been let down, the standards may be turned on their pivots 120 and returned into the housings, and the 130

covers or lids turned back to close the housings and finish the upper edge of the permanent body. By arranging the buttons 26' and the buttonholes 25 at the inside of the standards and curtains respectively, the curtain members may be secured or released by a person within the vehicle so that the entire body may be converted to a closed structure without the occupants leaving the vehicle.

10 Having thus described my invention, what I claim as new therein, and desire to secure by Letters Patent, is:

1. In a vehicle, a body comprising door openings and a body member between the openings, doors for closing said openings, each having end walls, and standards mounted in the adjacent end walls of said doors and overlapping above the said body member when the doors are closed and the standards are in functional position.

2. In a vehicle, a body comprising door openings and a body member between the openings, doors for closing said openings, each having end walls, standards mounted in the adjacent end walls of said doors and overlapping above the said body member when the doors are closed and the standards are in functional position, and with the standard on the forward door lying at the outside of the standard on the rear door.

3. In a vehicle, a body comprising door openings and a body member between the openings, doors for closing said openings, each having end walls, standards mounted in the adjacent end walls of said doors and overlapping above said body member when the doors are closed and the standards in

functional position, a top for the vehicle, and curtains coöperating with the body and top to inclose the vehicle.

4. In combination with a vehicle body, having chambers in its side walls, standards pivotally mounted on said body and adapted for housing within the chambers and for extension therefrom, curtains located within the chambers adapted for extension therefrom along the standards, the said curtains having grooved edges adapted for guided travel along the edges of the standards, for the purpose set forth.

5. In combination with a vehicle body, having a chamber therein, standards pivotally mounted on the body at opposite ends of the chamber and adapted for housing within said chamber, and for movement from the housing to perpendicular position, a curtain suspended within the chamber between the standards and adapted for extension therefrom, the ends of the curtain being bifurcated and straddling the facing edges of the standards.

6. In combination with a vehicle body, having a chamber therein opening through the upper edge of the body, standards pivotally mounted on the body and adapted for housing within the chamber, each standard having a shoulder adapted for lying over an adjacent portion of the body to limit the pivotal movement of the standard, a curtain movable into and from the chamber and having bifurcated end flaps for straddling the facing edges of the curtain.

In testimony whereof I affix my signature.

DANIEL G. SAUNDERS, JR.
